UNITED STATES PATENT OFFICE.

LENORE ZUEHLKE, OF HORTONVILLE, WISCONSIN.

ELECTRIC ORCHESTRION.

1,277,813.

Specification of Letters Patent.

Patented Sept. 3, 1918.

Application filed January 3, 1914. Serial No. 810,107.

To all whom it may concern:

Be it known that I, LENORE ZUEHLKE, a citizen of the United States, residing at Hortonville, in the county of Outagamie and

5 State of Wisconsin, have invented certain new and useful Improvements in Electric Orchestrions, of which the following is a specification.

My invention relates to musical instruments, and more particularly to musical instruments for playing automatically a combination of instruments, which are operated with electric striking or tapping devices, such as used in playing xylophones, harp 10 imitations, etc. It also comprehends wind-produced tones, such as violin imitations, cornet imitations, and all pipe tones which are operated through the aid of electric operating devices or air automatic devices connected in either case to small wind-operated bellows, whereby any selected notes of any selected instruments, or imitation of instruments, can be played independently of each other, and by which the various instruments 15 20 25 may be played in concert or independently.

The object of the device is to provide simple and effective mechanism for carrying out the above described result, which will be easy of control, durable, economically manufactured, and the parts thereof may be easily repaired or replaced with little difficulty.

In the drawings forming a part of this specification, and in which like symbols of reference represent corresponding parts in 35 the several views:—

Figure 1 is a front view, partly in section, of the device, with note sheet, pneumatics, and player mechanism;

Fig. 2 is a side view of the tracker bar, 40 and attendant mechanism;

Fig. 3 a sectional detail view of one of the pipes;

Fig. 4 a similar sectional view of a pipe and air chamber;

Fig. 5 a modification of the device without electrical connections;

Fig. 6 a transverse section of the modified form; and,

Fig. 7 a view of a pipe and air chamber 50 of the modification.

In the drawings the numeral 1 represents the perforated note sheet, cut especially for an instrument of this character; and being divided into sections 2, 3, 4, 5, 6, and 7, and 55 operating in conjunction with a tracker bar

8. These sections control different instruments, for instance 2' the xylophone; 3' the cello; 4' the violin; 5' the cornet; 6' a series of different toned bells; and 7' any other instrument, or tone quality, as desired. 60

9 is the feed roll; 10 the take-up; 11 exhaust chamber; 12 tubes leading from the tracker bar to vacuum chest; and 13 the bellows, forming part of a pneumato-electric device, which closes when a tube 12 is exposed through a perforation in the paper roll. 14 are tubes leading to the exhaust chamber; and 15 a connection extending to the battery 16. 17 represent the switches to control the electrical current. The wire or 65 metal connection is extended from 16 to 18, the instrument or tone qualities to be played.

When the bellows 13 of the pneumato-electric device closes a connection is made with 19 and 20; the connection 19 extending 70 to the batteries 16. A connection extends from each individual tone at the different instruments, to 21 on the bellows, which when closed form a circuit. 22 represent the supply chambers of the various instruments; 75 and 23 the pipes operated by an air pump, or the like.

In the modification shown in Fig. 5, I have illustrated another way in which the instruments may be operated without electrical connections. In this case the tones are controlled from the small bellows by a wire or similar connection 24 with the valves 25, which when the bellows close will operate 80 the individual note. 90

Of course any type of foot power pump or electrically operated pump, or any type used in player pianos may be employed to control the vacuum chest, and I have therefore thought it unnecessary to show the 95 same. By this instrument not only may a number of independent tones and instruments be played or imitated, but the operator has absolute control over the same as before described either to play some or all. 100

Having now fully described my invention, what I claim as new and desire to secure by Letters-Patent, is:—

An electric orchestrion comprising a note sheet, a tracker bar, an exhaust chamber, 105 tubes connecting the exhaust chamber with the tracker bar, a plurality of bellows connected to the chamber, the movable portion of each bellows extended to form a finger, a source of electricity, branch circuits leading 110

therefrom, switches in the circuits, each comprising a resilient contact part respectively operated to close the circuit by the bellows-fingers, magnets in the branch circuits controlling the sounding bodies, and other switches, one to control each instrument as a whole.

In testimony whereof I affix my signature in presence of two witnesses.

LENORE ZUEHLKE.
